UNITED STATES PATENT OFFICE

109,693

DESIGN FOR A ROBE

Simon Barsa, New York, N. Y.

Application March 17, 1938, Serial No. 75,899

Term of patent 3½ years

To all whom it may concern:

Be it known that I, Simon Barsa, a citizen of the United States of America, residing in the city of New York, State of New York, have invented a new, original, and ornamental Design for a Robe, of which the following is a specification, reference being had to the accompanying drawing, forming part thereof, wherein,

In the drawing the trimming disclosed consists of padded roll trimming material.

I claim:

The ornamental design for a robe, as shown and described.

SIMON BARSA.
